United States Patent Office

Des. 229,679

Patented Dec. 25, 1973

229,679

ARCHITECTURAL UNIT

Mark L. Hildebrand, Altadena, Calif.
(157 Bowers Hill Road, Oxford, Conn. 06483)

Filed Sept. 1, 1971, Ser. No. 177,197

Term of patent 14 years

Int. Cl. D25—01

U.S. Cl. D13—1 J

FIG. 11.

FIG. 1 is a top view of my architectural unit.

FIGS. 2 and 3 are perspective views of my architectural unit.

FIGS. 4 and 5 are, respectively, the right-side and back views of the architectural unit of FIG. 3.

FIGS. 6 and 7 are, respectively, cross-sectional views through 6—6 and 7—7 of FIG. 3.

FIGS. 8, 9 and 10 are, respectively, cross-sectional views through 8—8, 9—9 and 10—10 of FIG. 1.

FIG. 11 is a perspective view of my architectural unit.

I claim:

The ornamental design for an architectural unit, substantially as shown.
